R. B. BENJAMIN.
ELECTRICAL RECEPTACLE.
APPLICATION FILED OCT. 16, 1917.

1,284,564.

Patented Nov. 12, 1918.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL RECEPTACLE.

1,284,564.

Specification of Letters Patent. Patented Nov. 12, 1918.

Application filed October 16, 1917. Serial No. 196,814.

To all whom it may concern:

Be it known that I, REUBEN B. BENJAMIN, a citizen of the United States, residing at Chicago, in the county of Cook and State 5 of Illinois, have invented new and useful Improvements in Electrical Receptacles, of which the following is a full, clear, concise, and exact description, reference being had to the accompanying drawing, forming a 10 part of this specification.

My invention relates to an electrical receptacle.

One of the objects of my invention is to provide an improved receptacle equipped 15 with means for holding a lamp-base in position and to prevent it from becoming accidentally unscrewed from the receptacle. Further objects will appear from the detailed description to follow and from the 20 appended claims.

In the drawings, in which two embodiments of my invention are shown—

Figure 1 is an axial section of a receptacle embodying my invention;

25 Fig. 2 is a section on the line 2—2 of Fig. 1, looking in the direction of the arrows;

Fig. 3 is a section on the line 3—3 of Fig. 2, looking in the direction of the arrows;

20 Fig. 4 is a fragmentary side elevation of 30 a portion of the receptacle;

Fig. 5 is a section on the line 5—5 of Fig. 2, looking in the direction of the arrows;

Fig. 6 is an elevational view showing the 35 leaf-spring for engaging the lamp-base;

Fig. 7 is a section on the line 7—7 of Fig. 6, looking in the direction of the arrows;

Fig. 8 is an elevation of another form of 40 leaf-spring which may be used;

Fig. 9 is a section on the line 9—9 of Fig. 40 8; and

Fig. 10 is a detail sectional view showing the manner in which the leaf-spring of Fig. 8 may be secured to the shell contact.

Referring now to the drawings in detail, 45 and first to the form of Figs. 1 to 7, inclusive, the receptacle shown comprises an insulating base or support 15, center and shell contacts 16 and 17, respectively, supported by the insulating base 15, and binding-terminals 18 and 19, respectively, for the contacts 16 and 17. The center contact 16 and the binding-terminal 18 may be secured in place on the base 15 by means of an eyelet 20, and the shell contact 17 and binding-

terminal 19 may be held in position on the 55 base 15 by means of an eyelet 21.

The shell contact 17 is provided with a helical, inwardly-extending bead 22, which forms a thread for engagement with the threaded contact of the lamp-base. This 60 bead is interrupted for about two-thirds of a turn, whereby an inwardly-opening, outwardly-closed pocket 23 is formed, in which is located a leaf-spring 24, which exerts pressure on the threaded contact of the 65 lamp-base to prevent it from unscrewing from the receptacle. This leaf-spring 24 is reduced at its central portion as indicated at 25, and this reduced portion 25 is secured beneath a tongue 26 struck up from the shell 70 contact 17 (Fig. 3). The ends of the leaf-spring 24 extend through openings 27 in the shell contact 17, the ends having a slight sliding motion in these openings to permit the springing of the portions of the leaf-spring intermediate the openings 27 and the tongue 26. These intermediate portions of the leaf-spring may be reduced in breadth, as indicated at 28, in order the better to 75 enter the trough of the thread of the lamp-base.

In operation, when the lamp is screwed into the receptacle, the threaded contact of the lamp-base engages the thread of the contact 17 formed by the bead 22 and is thus 80 threaded into the receptacle.

The leaf-spring 24 engages the threaded contact of the lamp-base with a yielding pressure and prevents it from coming unscrewed due to jarring, etc. 90

In the form of my invention, shown in Figs. 8, 9, and 10, the parts may be the same as in the form just described with the exception of the leaf-spring in its connection with the threaded shell. In this form the leaf-spring 29 has an aperture 30 in its intermediate portion, through which extends a tongue 31 struck up from the shell contact 17, the tongue 31 being riveted over to hold the leaf-spring 29 firmly in position. The 95 ends 32 of this leaf-spring are reduced to form tongues for extending through the openings 27 in the threaded shell contact. The portions 33 of the leaf-spring intermediate the central portion and the ends 32 100 are curved in cross-section, as indicated in Fig. 9, to conform to the trough of the thread of the contact on the lamp-base. The 105

use and operation of this form is the same as in the form previously described.

In making the threaded shell contact 17, the material is first formed into a smooth cylindrical cup. The bead 22 is then formed by means of rolls, one inside the shell and one outside the shell, the roll inside the shell having a groove corresponding in shape to the bead 22, and the roll outside of the shell having a bead or rib corresponding in shape to the bead 22. This bead on the outside roll forces the material of the shell 17 into the groove on the inside roll. The interruption in the bead 22 is arrived at simply by omitting a portion of the bead in the outside roll. Thus, the pocket for the spring lamp-grip may be formed without any increase in cost of manufacture.

I claim as new and desire to secure by Letters Patent of the United States:

1. An electrical receptacle comprising an insulating support; a sheet-metal screw-shell contact supported thereby, the thread of said shell contact being interrupted to form a helically-extending, inwardly-open, outwardly-closed pocket integral with said shell; and a spring located in said pocket for retaining a lamp-base in position.

2. An electrical receptacle comprising an insulating support; a sheet-metal screw-shell contact supported thereby, the thread of said shell contact being interrupted to form a helically-extending, inwardly-open, outwardly-closed pocket integral with said shell; and a helically-extending leaf spring located in said pocket for retaining a lamp-base in position.

3. An electrical receptacle comprising an

insulating support; a sheet-metal screw-shell contact supported thereby, the thread of said shell contact being interrupted to form a helically-extending, inwardly-open, outwardly-closed pocket integral with said shell; and a helically-extending leaf spring located in said pocket for retaining a lamp-base in position, said leaf spring having spaced portions bearing on said shell contact and a portion intermediate said spaced portions for bearing on a lamp-base.

4. An electrical receptacle comprising an insulating support; a sheet-metal screw-shell contact supported thereby, the thread of said shell contact being interrupted to form a helically-extending, inwardly-open, outwardly-closed pocket integral with said shell; and a helically-extending leaf spring located in said pocket for retaining a lamp-base in position, said leaf spring having spaced portions bearing on said shell contact and a portion intermediate said spaced portions for bearing on a lamp-base, said intermediate portion being curved in transverse section to conform to the trough of the thread of the lamp-base.

5. An electrical receptacle comprising an insulating support; a sheet-metal screw-shell contact supported thereby, said shell contact having a circumferentially-extending, inwardly-open, outwardly-closed pocket integral with said shell; and a spring located in said pocket for retaining a lamp-base in position.

In witness whereof I have hereunto subscribed my name.

REUBEN B. BENJAMIN.
